(57) **CLAIM**

I claim the ornamental design for a pot holder with flower, as shown and described.

DESCRIPTION

FIG. 1 is a perspective view of a pot holder with flower;
FIG. 2 is a front view thereof, shown at a reduced scale;
FIG. 3 is a rear view thereof;
FIG. 4 is a right side view thereof;
FIG. 5 is a left side view thereof;
FIG. 6 is a top view thereof;
FIG. 7 is a bottom view thereof; and,
FIG. 8 is a perspective view thereof, shown in an environment of use.
The broken lines depict environmental subject matter only and form no part of the claimed design.
